UNITED STATES PATENT OFFICE.

JUDSON L. MCKELLAR, OF BROOKLYN, NEW YORK, ASSIGNOR TO GASAU-THOMPSON COMPANY, INC., OF BROOKLYN, NEW YORK, A CORPORATION OF NEW YORK.

METALLIC SPRING MATTRESS.

Application filed November 6, 1919. Serial No. 336,153.

To all whom it may concern:

Be it known that I, JUDSON L. MCKELLAR, a citizen of the United States, and a resident of Brooklyn, in the county of Kings 5 and State of New York, have invented certain new and useful Improvements in Metallic Spring Mattresses, of which the following is a specification.

The invention relates to improvements in 10 metallic spring mattresses or bed-bottoms, and it consists in the novel features and structure hereinafter described, and particularly pointed out in the claims.

One object of the invention is to provide 15 a very durable metallic spring mattress capable of ready manufacture and not liable to the sagging condition to which many spring mattresses are subject. The main portion of my metallic spring mattress consists, in addition to the ordinary end rails and helical coils connected therewith, of a series of integral strands folded over at their middle portions to form two members, said strands at their folded over or bent 20 portions being secured to one set of the helical coils and at their other end having their members secured together by clips and connected with the other set of helical coils, said clips being secured within such coils.

25 The spring mattress of my invention also comprises a special disposition of the members of the strands, such members being held on repeating diverging angles so as to produce a diamond effect in the spring throughout the body portion thereof. One of the essential features of my invention and which adds greatly to the beneficial character of the structure as a whole, consists in the fact that the individual strands 30 are not only continuous, but comprise an inner stout core of wire and an outer covering of closely coiled wires of smaller diameter enclosing such core.

The invention will be fully understood 35 from the detailed description hereinafter presented, reference being had to the accompanying drawings, in which:

Fig. 1 is a top view, partly broken away, of a metallic spring mattress or bed-bottom

constructed in accordance with and embodying my invention;

Fig. 2 is a side elevation, partly in section, of a portion of the same and on a larger scale;

Fig. 3 is an enlarged transverse section 55 through a portion of the same, taken on the dotted line 3—3 of Fig. 2;

Fig. 4 is a vertical longitudinal section 60 through a portion of the same, taken on the dotted line 4—4 of Fig. 3;

Fig. 5 is a transverse section through a portion of the same, taken on the dotted line 5—5 of Fig. 3;

Fig. 6 is a detached perspective view of 65 one of the clip-blanks by which the free ends of the looped longitudinal strands of the spring may be securely fastened together, and

Fig. 7 is an enlarged transverse section 70 through a portion of the spring, taken on the dotted line 7—7 of Fig. 1.

In the drawings, 10 designates the two angle-iron end rails of the bed-bottom, these end-rails being of usual construction and secured to the upper ends of the bracket- 75 arms 11 which are secured at their lower ends to the main connecting rods or side-rails 12, as usual.

The spring portion of the bed-bottom is composed of a series of duplex strands 13 80 each in one integral piece folded upon itself to form the two members 14, 15 which are integrally connected at one end by a bend or loop 16 and at their opposite end, this representing the two free ends of the 85 strand, by means of metal clips 17 shown more fully in Figs. 3 to 6 inclusive. Each strand 13 is formed in a continuous piece and each comprises an inner rod of wire 18 extending throughout the entire length 90 of the strand, and an outer tubular member 19 formed from a series of correspondingly coiled wires entirely enclosing the wire 18, which constitutes a substantial core for the strand. It will be obvious that the close 95 winding of the tubular member 19 from relatively thin wires provides a resilient covering member or element. The duplex

strand 13 is folded over at its middle portion to form the loop or bend 16, and the several strands at the loop or folded over portion 16 thereof are hooked upon the inner ends of helical springs 20, as shown in Fig. 1. The free ends of the members of the strands 13 are brought together, as shown in Fig. 3, and bound together by a sheet metal clip 17 whose initial form is somewhat in the outline of an inverted U, as shown in Fig. 6, the blank for the clip 17 having a top which is longitudinally grooved, as at 21, to form a rib entering partly between the members of the strand 13 and said clip also having side portions 22 adapted to pass upon the opposite sides of the ends of the members of the strand and be closely pinched around and upon the same so that finally the clip takes the outline represented in Fig. 5 closely encompassing and binding against the free end portions of the strand members 14, 15. In applying the clip 17 to the ends of the strand members 14, 15 I not only firmly close the clip around the said members, but crimp the clip and said end portions, as indicated at 23, whereby I am enabled to so securely fasten the free ends of the strand members together that neither can pull out from the clip 17. One end of each strand 13 is fastened at its bent or folded over middle portion 16 by being hooked upon one of the helical springs 20, and the other end of each strand, adjacent to the clip 17, is fastened to a helical coil 24 by means of a hook 25 formed out of the wire of the coil and extending between the strand members 14, 15 adjacent to the clip 17, said clip 17 and the adjacent ends of the strand members 14, 15 being concealed within the coil 24, as shown in Fig. 3.

The strands 13 are connected together by means of metallic stays 26, which are transversely disposed and, at suitable points, connect the member 14 of one strand with the member 15 of the adjacent strand, and at points between the several stays 26 the members of each strand are connected together by metallic stays 27. Throughout the main body of the mattress the members of the strands 13 are considerably separated from each other and given a somewhat diamond effect from the fact that the stays 26 hold the members of the strands pulled outwardly from each other and that the stays 27 hold the members of each strand in a partly drawn together relation, as clearly represented in Fig. 1, and I have found that this diamond effect distributed over the mattress by reason of the special relation of the stays 26, 27 acting to hold the members of the strands on diverging and converging lines approximating a diamond shape, adds greatly to the general character of the mattress as a spring sup-

port and also aids materially in preventing the sagging of the mattress. The construction is one presenting great durability, and its parts may be readily manufactured and assembled without undue expense. The durability and general character of the spring is enhanced from the presence of the stout wire rod 18 within the members of the several strands and the fact that in the use of the mattress and the bending of the wire cores 18, the covering coils 19 may yield therewith and not only be supported thereby, but add support to the wire cores.

There are many advantages for using a finer wire to form the wire coils and for so closely winding this wire on the core. Among these advantages are the strength and durability of the resulting fabric without doing away with the proper resiliency thereof.

In other words, the close winding of the wire coils very materially strengthens the fabric as compared with one in which the coils are not wound close. Not only this but the close winding of the coils enables the coils to maintain their position at all times so as not to move toward and from each other, whereas the coils of a loosely wound covering would move toward and from each other and not maintain their proper positions in use and would soon get out of shape. Moreover, the closely wound coils prevent the bed enamel in which the spring is dipped from getting on the inside of the coils where it would form in patches and be tacky and likely to run out at some time when the spring was in use to the injury of any fabric in contact therewith.

Moreover, the closely wound coils prevent vermin from getting on the inside of the coils, which would not be the case were the coils loosely wound. Furthermore, the closely wound coils enables a finer wire to be used than the core itself. The use of a heavy wire for the coils would not only be expensive and difficult to coil, but would make the spring too heavy to handle and too expensive to sell, whereas by winding the coils in close relation a finer wire can be used and yet have greater strength than a materially heavier wire loosely wound. Were the coils loosely wound they would also stretch apart, and so move toward and from each other when the fabric was in use, and this movement of the coils toward and from each other would wear and also pinch the stuffed mattress fabric and tend to tear it, but by having the coils closely wound this disadvantage is entirely avoided, since there is no opportunity for the fabric to get between the coils.

Furthermore the closely wound coils enables the use of the clips or clamps hereinbefore referred to in a practical manner, which would not be possible with loosely wound

coils, since the clamp would not hold securely on loosely wound coils as these coils would stretch. In short, by having the coils closely wound they can be made of finer wire, whereby they are more effectively wound and the expense of the structure materially reduced, and yet that structure very materially strengthened, and these closely wound coils so materially strengthen the structure that the sagging of the spring fabric is very materially prevented. In fact it has been found in practice that a spring fabric made up of the wire cores alone would materially sag, but with the spiral closely wound coils thereon this sagging is to a large extent eliminated, thus materially strengthening the fabric and doing away with that objectionable sagging present in many spring mattresses, without affecting the proper resiliency thereof.

Thus I am able to provide an improved fabric in which each lengthwise member comprises a single wire core and finer wire coils closely wound to form a spiral tubular covering materially strengthening the core and preventing undue sagging of the fabric without affecting the proper resiliency thereof.

At its opposite side portions the mattress or bed-bottom is formed with strands 28, 29 which are identical with the strands 13, except that said strands 28, 29 have their members brought close together, so that the strands are parallel with each other. The strands 28, 29 are connected together by stays 30, and the strands 29 are connected by metallic stays 31 with one straight member of an adjoining strand 13. The ends of the strands 28, 29 are connected with helical springs 32, 33, respectively, which are secured to the head and foot angle-bars 10 and are closer together than the springs 20 so that at the side edges of the bed said strands 28, 29 may afford a more rigid support than the strands occupying the main body of the mattress.

My invention therefore resides in a spring mattress or bed-bottom having rigid end rails or bars connected by the endless strands 50 of the character hereinbefore described, each consisting of two members integrally connected at one end and secured together by a clip at the other end, and each strand comprising an inner comparatively thick flexible 55 strong wire core 18 and an outer covering 19 formed of materially finer closely spirally coiled wires, and said strands being secured at opposite ends to helical coils and at intermediate portions by stays 26, 27, as hereinbefore described.

The helical spring coils, 20, 24, 32 and 33 are identical in construction and each thereof is formed with a hook, as 25, to engage the strands 13, 28 and 29, and the coils 24, 65 33 substantially conceal the clips employed

to fasten the free ends of the members of the respective strands together.

What I claim as my invention and desire to secure by Letters Patent, is:

1. A spring fabric for spring mattresses made up of substantially parallel members, each comprising a stout central wire core element, and a covering element of closely wound coils formed of a plurality of wire strands on said core, one of said elements being inherently resilient.

2. A spring fabric for a spring mattress made up of substantially parallel members, each comprising a stout central wire core element, and a covering element of closely wound coils formed from a plurality of wire strands, one of said elements being inherently resilient, and said coils being formed of wire materially finer than the wire of said core.

3. A spring fabric for a spring mattress made up of substantially parallel members, each comprising a stout central wire core, and an inherently resilient covering of closely wound coils formed from a plurality of wire strands on said core.

4. A spring fabric for a spring mattress made up of substantially parallel members, each comprising a stout central wire core and an inherently resilient covering of closely wound coils formed from a plurality of wire strands on said core, said coils being formed of wire materially finer than the wire of said core.

5. A spring fabric for a spring mattress made up of substantially parallel members each comprising a stout central wire core element, and a covering element of closely wound coils formed from a plurality of wire strands on said core, one of said elements being inherently resilient, and metal clips clamped on the end portions of said members for binding them together.

6. A spring fabric for a spring mattress made up of substantially parallel members each comprising a stout central wire core element and a covering element of closely wound coils formed from a plurality of wire strands on said core, one of said elements being inherently resilient, and metal clips clamped on the end portions of said members for binding them together, the said coils being formed of wire materially finer than the wire of said core.

7. A spring fabric for spring mattresses made from lengthwise extending wire formed members, each comprising a stout central wire core element, and a tubular covering element of loosely wound spiral wire coils loose on said core, one of said elements being inherently resilient.

8. A spring fabric for spring mattresses made up of lengthwise extending wire members, each comprising a stout central wire coil element and a tubular covering element

of closely wound wire spiral coils loose on said core, said covering element being inherently resilient, and the strength of the core be materially increased by the close winding of the coils thereby preventing sagging of the fabric.

Signed at Brooklyn, in the county of

Kings and State of New York, this 3rd day of November, A. D. 1919.

JUDSON L. McKELLAR.
